US0D1003634S

(12) **United States Design Patent** (10) **Patent No.:** **US D1,003,634 S**
(45) **Date of Patent:** **** Nov. 7, 2023**

(54) **MATTRESS**

(71) Applicant: **Shenzhen Kaysno Technology Co., Ltd.**, Shenzhen (CN)

(72) Inventor: **Jianqiang Huang**, Shenzhen (CN)

(73) Assignee: **Shenzhen Kaysno Technology Co., Ltd**

(**) Term: **15 Years**

(21) Appl. No.: **29/790,002**

(22) Filed: **Oct. 29, 2021**

(51) LOC (14) Cl. **06-09**

(52) U.S. Cl.

USPC **D6/605**
